UNITED STATES PATENT OFFICE.

JOHN F. GROHOWSKY, OF KINGSTON, PENNSYLVANIA.

TROLLEY-CONTACT.

1,126,989.

Specification of Letters Patent.

Patented Feb. 2, 1915.

Application filed May 10, 1913. Serial No. 766,906.

To all whom it may concern:

Be it known that I, JOHN F. GROHOWSKY, a citizen of the United States, residing at Kingston, in the county of Luzerne and State of Pennsylvania, have invented a new and useful Trolley-Contact, of which the following is a specification.

The present invention relates to improvements in an electrical contactor for use in connection with electrical switch operating means for trolley railways, the said contactor being so constructed as to be readily clamped upon the trolley wire without cutting or bending the wire, thus rendering it possible to attach the same at any point along the right of way that it is desired to operate electromagnetically controlled switch point mechanisms, and especially of that type where the electromagnets are controlled due to the position of the controller of the motor car.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a diagrammatic view illustrating the present invention. Fig. 2 is a side elevation of the trolley carried member at the point of operation of the switch. Fig. 3 is a section taken on line 5-5 of Fig. 2.

Referring to the drawings, the numeral 1 designates an overhead trolley wire, although it is to be understood that the present device may be used in connection with an underground trolley system, the said wire having disposed thereabout, the device as shown particularly in Figs. 2 and 3, which constitutes a shunting means for operating the switch point, as will presently appear, due to the position of the trolley wheel relatively to such device and the manipulation of the controller C, as illustrated in Fig. 1. The trolley wire 1 at this point is incased with the member, which includes the carrying portion 2, the spaced and insulated plates 3 and 4, the insulated sectional bushings 6 and 6' which are fitted between the plates 3 and 4 and carried by the supporting member 2 through the rim

by the screws 5, and the insulating bushings 7 and bolts 8. By this means, the trolley is properly incased at this point, and the device 2 may be supported from any form of support similar to the cross over and trolley supports as now used.

Positioned adjacent the device 2, along the right of way, is a vertical post 10, which carries the mechanism incasing cabinet 9 which may be of any desired construction and may be positioned in ready access to the operatives of the road. A conductor is led from the trolley 1 to the post 10 and is connected to the solenoid 12 disposed within the cabinet 9 while the conductor 13 is led from the solenoid and is connected to the metal plate 4 of the device 2. The method of controlling the solenoid 12 will be set forth later on, the detail description of the installation being set forth at the present time.

A conductor 14 is led from the metal plate 3 and through the resistance 15, which is preferably composed of powdered graphite, a conductor 16 being led therefrom to the contact plate 17 carried upon the lower end of the solenoid core 18, said core 18 extending vertically through the solenoid 12 within the insulating sleeve 12' thereof. Carried upon the upper end of the core 18, is a metal disk 21, while disposed in fixed relation upon the opposite ends of the solenoid 12 and insulated therefrom, are the two metal plates 19 and 20, the purpose of which will presently appear.

When the parts are in normal position, as clearly shown in Fig. 1, the core 18 being in its lowermost position, the disk 21 is in contact with the plate 20 and thus any current passing through the core 18 will continue to the plate 20 and through the conductor 23 to the switch operating solenoid 24 which is grounded at 25. When the solenoid 12 is energized sufficiently to elevate the core 18, the metal contact 20 will be disengaged from the contact plate 21, while the plate 17 will be engaged with the contact plate 19, thus causing the current to flow through the conductor 26 to the switch operating solenoid 27 which operates in opposition to the solenoid 24 and is grounded as at 28.

The two solenoids 24 and 27 are adapted to be operated selectively, due to the manipulation of the controller C of the motor car, and when the trolley wheel W is bridging the contact plates 3 and 4 of the device 2.

The conductor 29 is led from the pole P in the usual manner through the controller C and the motors M of the car to the ground G. Assuming that the car is approaching and the motorman desires to select and operate the solenoid 24, the controller C is closed so that no current is flowing to the motors M and as the trolley wheel W bridges the plates 3 and 4, a certain portion of the current will be shunted from the trolley 1 but will be of insufficient capacity to energize the solenoid 12, the core 18 remaining in the position, as clearly shown in Fig. 1, so that the current to the solenoid 24 will flow as follows: the trolley wire 1, the conductor 11, the solenoid 12, the conductor 13, the contact plate 4, the wheel W, the contact plate 3, the conductor 14, the resistance 15, which is in reality a slight choking means to protect the respective solenoids 24 and 27 from too great a charge of current, the conductor 16, the contact 17, the core 18, the contact 21, the contact plate 20, the conductor 23, the solenoid 24 and the ground 25. Now assuming that the next following car desires to operate the solenoid 27 and proceed in a direction opposite to the preceding trolley car, the motorman opens the controller C and thus the full current of the motors is drawn through the solenoid 12, elevating or attracting the core 18, opening the contacts 20 and 21 and closing the contacts at 17 and 19. The circuit thus closed will energize the solenoid 27 and will flow as follows: the trolley 1, the conductor 11, the solenoid 12, the conductor 13, the contact plate 4, the wheel W, the contact plate 3, the conductor 14, the resistance 15, the conductor 16, the core 18, the contact plate 17, the same as before described being elevated to contact the plate 19, the conductor 26, the solenoid 27 and the ground 28. Thus the solenoid 27 is energized and the switch point (not shown) is operated or moved in an opposite direction to the action thereof when the solenoid 24 was previously energized.

In order to provide a means whereby the switch point (not shown) will be moved to the various desired positions, the cores (not shown) of the two solenoids 24 and 27 are connected by a rod 30, said rod 30 being operably connected to a pendant lever 33, which is pivoted at 34 within the casing 32, said casing 32 and both solenoids being incased in a main casing (not shown) disposed

in proper position relatively to the switch point (not shown). The rod 37 is connected to be operated by the lever 33 and in turn operates the switch point (not shown).

From the foregoing description, taken in connection with the drawings, it is evident that with an installation of the present character, which also is as readily applied to an underground trolley system as it is to an overhead trolley and is therefore especially adapted for use in connection with urban and inter-urban traffic, as well as mines, it is evident that a single switch actuating solenoid as disposed in the casing 9 may be employed to select the manipulation or control of the respective solenoids 24 and 27, so that the switch point 40 may be operated to divert traffic either to the right or left and as before stated through a single instrumentality instead of as is the present custom manipulating a single electro-motor at predetermined points of traffic.

What is claimed is:

1. A contactor, including a block of insulation having oppositely extending portions grooved longitudinally to fit upon a trolley wire, a strip of insulating material substantially semi-circular in cross section and grooved to fit upon the under side of the trolley wire and coöperate with the block of insulation to incase the trolley wire, and two metal contact plates attached to the block of insulation and having wheel engaging portions embracing the strip of insulation, but out of contact with each other to clamp the contactor to the trolley wire.

2. A contactor, including a block of insulation having oppositely extending portions grooved longitudinally to fit upon a trolley wire, a strip of insulating material substantially semi-circular in cross section and grooved to fit upon the under side of the trolley wire and coöperate with the block of insulation to incase the trolley wire, two metal plates each having a flat and a curved portion, and means for securing the plates so that the curved portions clamp the block and strip upon the trolley wire.

In testimony that I claim the foregoing as my own, I have hereto affixed my signature in the presence of two witnesses.

JOHN F. GROHowsky.
